UNITED STATES PATENT OFFICE.

WALTER BIDDLES, OF LEICESTER, ENGLAND.

GEAR-CASE.

SPECIFICATION forming part of Letters Patent No. 531,254, dated December 18, 1894.

Application filed September 4, 1894. Serial No. 522,132. (No model.) Patented in England October 5, 1893, No. 18,621.

To all whom it may concern:

Be it known that I, WALTER BIDDLES, a subject of the Queen of Great Britain, residing at Leicester, in the county of Leicester, England, have invented a new and useful Improvement in Gear-Cases, (for which I have obtained a patent in Great Britain, No. 18,621, and bearing date October 5, 1893,) of which the following, taken with the drawings attached hereto, is a full and complete specification.

My invention relates to an improved case for inclosing and covering the chain driving gear of cycles and like vehicles, and it consists, as applied to cycles, of a foundation piece adapted to be brazed or otherwise fixed to the member of the fork or frame adjacent to the driving gear, of a case or cover formed in two parts, the one part adapted to cover the upper part of the chain driving gear and the other to cover the lower part thereof the said lower part having a window giving a view of the interior of the case, the said two parts of the case being fixed to the foundation piece and to each other by means of one or more screws, the object being to obtain a gear case which can easily and readily be detached for the purpose of cleaning, adjusting, or effecting any necessary repairs to the cycle or case, and which is oil retaining, and to enable the amount of oil or dirt in the case or the condition of the chain to be seen at a glance. I attain this end in the manner shown by the accompanying drawings, in which—

Figure 1 is a view in side elevation showing the application of my improved gear case to a cycle by way of illustration. Fig. 2 is a view showing the two parts of the case detached from the foundation piece. Fig. 3 is a view in plan of the foundation piece fixed to the frame of the cycle. Figs. 4, 5 and 6 are views in transverse section on lines v, v ; x, x ; and z, z , Fig. 1, respectively, and Figs. 7 and 8 are views in transverse section showing alternative methods of constructing the window.

Throughout the views similar parts are marked with like letters of reference.

The gear-case is formed in two parts A and A', the top part A being adapted to cover the top half of the chain driving gear, and the part A' to cover the lower half thereof.

The two parts of the gear case meet at a line

drawn between the centers of the axles of the pedal-crank axle and driving wheel respectively, the edges of the front and back sides of the parts A and A' being cut away, as at a and a' respectively to clear the member Y of the fork or frame, to which the foundation piece is attached.

The top part A of the case has small depending strips a^2 adapted to overlap the edges of the lower part A' of the case and of the plates B and B' of the foundation piece so that any oil on the inner surface of the case will be thrown or conducted down into the bottom of the case.

The bottom part A of the case has recesses a^3 formed on the surfaces of its inner sides to receive the edges of the plates B and B' of the foundation piece. The two plates B and B' forming the foundation piece are connected together by a horizontal strip b preferably so arranged that the member Y of the frame bears on it and can be conveniently brazed, soldered, or otherwise attached to it.

The two parts A and A' of the case are fixed to each other and to the foundation piece by one or more screws D. When but one fixing screw is used it is preferably located at or about the center of the length of the case, and small depending pieces A^2 are formed on or fixed to the sides of the top part A of the case to receive the said screw which passes through holes in the lower part of the case A' and through a socket C carried by the strip b of the foundation piece, the screw D being adapted to screw or thread into the piece A^2 on the back of the part A of the case as shown by Fig. 5. The socket C carried by the strip b of the foundation piece prevents the case from being drawn or forced out of shape by the fixing screw D.

The rear ends of the plate B of the foundation piece and of the parts A and A' of the case are slotted to receive the axle and part of the hub of the driving wheel to provide for the adjustment of the driving gear, the slot in the plate B being covered by a plate E adapted to be placed on the said axle and the slot formed by and between the two parts A and A' of the case being covered by two plates F and F' adapted to be placed round the hub of the driving wheel between the chain wheel and flange thereof and to slide

in or on the back side of the said parts of the case.

Instead of fixing the two parts to the foundation piece together they may each be fixed 5 to the said foundation piece independently so as to be capable of separate removal.

To provide a means of ascertaining at a glance the amount of dirt or oil in the case, or the condition of the driving chain, or the 10 connecting pin and nut thereof, I fit the lower part of the case in any convenient position with a small window H, as shown by Figs. 1 and 2. This window is preferably made of a circular form as shown as it is then easy to 15 remove and may also be used as the orifice for introducing oil into or removing oil from the case, but it may also be of a square or rectangular shape. The window may be glazed with glass, mica, talc, or any other 20 suitable transparent material.

When the window is of a circular shape I prefer to construct it in the following manner:—I take a circular ring h to form the frame and fix it to the side of the gear case either 25 by screwing it therein as shown by Fig. 7, or by soldering, brazing, or otherwise attaching it thereto. This ring frame h is threaded internally to receive a threaded ring h' which is adapted to lock the piece of glass h², or its 30 equivalent, against a shoulder h³ in the frame h, a leather ring washer h⁴ being interposed to make a good joint. When the window is made of a square or rectangular shape, the 35 piece of glass h², or its equivalent is fixed to the side of the gear case by means of a frame h⁵ and washer h⁶, by means of the screws h⁶ as shown by Fig. 8.

I wish it to be particularly understood that I do not limit myself to the precise details of 40 construction hereinbefore described and illustrated by the accompanying drawings, but that I hold myself as liberty to make such changes and alterations as fairly fall within the spirit and scope of my invention.

Having now particularly described and ascertained the nature of my said invention and in what manner the same is to be performed, 45 I declare that what I claim is—

1. In a case for inclosing and covering the chain driving gear of cycles and like vehicles, 50 the combination with a case formed in two parts such as A and A', of a foundation piece formed essentially of two plates such as B and B' and a junction strip such as b, as and for the purpose set forth.

2. In a gear case, the combination of the case formed in two parts A and A' the former having overlapping strips a² and the latter a window such as H, and of the foundation piece consisting of the two plates B and B' and the 60 strip b, all combined, arranged and adapted to operate, as and for the purpose set forth.

3. In a gear case, the combination of the case formed in two parts A and A' the former having overlapping strips a² and the latter a 65 window such as H, of the foundation piece consisting of the two plates B and B' and the strip b, of the socket C carried by the foundation piece, and of the screw D, all combined, arranged and adapted to operate, as 70 and for the purpose set forth.

4. In a gear case, the combination of the case formed in two parts A and A' the former having overlapping strips a² and the latter a window such as H, of the foundation piece 75 consisting of the two plates B and B' and the strip b, of the socket C carried by the foundation piece, of the screw D, and of the sliding plates E, F and F', all combined, arranged and adapted to operate, as and for the purpose set forth.

5. In a gear case, the combination with the case formed in two parts such as A and A', of the plates A², and the overlapping strips a² on the part A of the case, of the window H, 85 of the foundation piece consisting of the two plates B and B' and the strip b, of the socket C carried by the foundation piece, of the screw D, of the sliding plate E, and of the compound sliding plate F, F', all combined, 90 arranged and adapted to operate, as and for the purpose set forth.

WALTER BIDDLES.
